UNITED STATES PATENT OFFICE

109,161

DESIGN FOR A TRAILER

Clifford Brooks Stevens, Milwaukee, Wis., assignor to William Woods Plankinton, Milwaukee, Wis.

Application November 9, 1936, Serial No. 65,797

Term of patent 14 years

To all whom it may concern:

Be it known that I, Clifford Brooks Stevens, a citizen of the United States, residing at Milwaukee, in the county of Milwaukee and State of Wisconsin, have invented a new, original, and ornamental Design for a Trailer, of which the following is a specification, reference being had to the accompanying drawing, forming part thereof.

Both sides of the trailer have the same appearance.

I claim:

The ornamental design for a trailer as shown and described.

CLIFFORD BROOKS STEVENS.
